UNITED STATES PATENT OFFICE.

IVER JOHNSON, OF VANCOUVER, BRITISH COLUMBIA, CANADA, ASSIGNOR TO NICHOLAS COOK, OF SEATTLE, WASHINGTON.

CLOTHES-LINE PULLEY.

1,143,910.

Specification of Letters Patent. Patented June 22, 1915.

Application filed March 25, 1913. Serial No. 756,682.

To all whom it may concern:

Be it known that I, IVER JOHNSON, a citizen of the United States, residing at Vancouver, in the Province of British Columbia and Dominion of Canada, have invented 5 certain new and useful Improvements in Clothes-Line Pulleys, of which the following is a specification.

This invention relates to improvements in 10 clothes-line pulleys and has for its object the provision of a pulley of the class described of simple and economical construction, that is particularly efficient and useful in the work for which intended.

15 A further object of the invention is the provision with the pulley, of guide-bars of novel construction for leading the line to the groove about the pulley-wheel.

The invention consists in the novel construction 20 of the pulley-wheel and particularly in the adaptation of means for securing the plates of a two-part wheel together to avoid the use of rivets or the like.

The invention still further consists in the 25 novel construction and adaptation of guiding means for the line and the combination therewith of a supporting frame and wheel, as will be fully described in the following specification, illustrated in the accompanying 30 drawings, and finally set forth in the appended claims.

In said views, Figure 1 is a view in side elevation of devices embodying my invention. Fig. 2 is an end view of Fig. 1. Fig. 3 is a cross-sectional view through 3—3 of 35 Fig. 1. Fig. 4 is a fragmentary cross-sectional view of the pulley-members illustrating the preferred manner of securing the same together.

40 Referring to said drawings, the reference numeral 1 designates a pulley-wheel rotatably mounted on a pin 2 which is supported in a metal strap 3 extending symmetrically upon each side of the pulley in normally 45 horizontal directions. At its rear end said strap is formed with a loop 4 through which it is secured by staple or other device, not shown, to a fixed support. Said pulley-wheel is desirably composed of two pressed 50 metal plates 12 and 13 rigidly connected together and severally formed about their perimeters with an annular channel that corresponds when fitted together to form a deep-seated circumferential groove 5 for the 55 reception of a clothes-line, or the like, in-

dicated by dotted lines 6. Said strap is extended forwardly of the wheel, as at 7, whereat a guide-bar 8 is fixedly secured. The guide-bar is preferably formed of a strip of metal folded upon itself to afford at 60 its two opposite extremities eye-openings 9 in line with the groove 5 upon diametrically opposite sides of the pulley, respectively. The guide-bar may be secured to the strap, as indicated in the views, by spreading the 65 medial portion of the folded strip to afford an opening 10, see Fig. 2, through which the ends 11 of the strap 3 are projected and pressed backwardly upon the outside of said medial portion providing a rigid and reliable fastening. The two wheel members 12 and 13 are each provided with a plurality of tongues 14 which are punched from the 70 respective members to project at right angles to the planes of the inner faces of the latter. The apertures 15 thus provided in a member are spaced so that the tongues of the other member will extend therethrough when the members are in juxtaposition as 75 illustrated in Fig. 4. The protruding ends of the tongues of each member are then bent down over the outer faces of the other member, as indicated by broken lines in Fig. 4 and by full lines in Fig. 3, thereby rigidly 80 uniting the wheel members. 85

The eye-openings 9 of the guide-bar serve to lead the line tangentially to and from the wheel groove when the wheel is rotated through the instrumentality of the line; said guide-bar furthermore serves to prevent the line from becoming displaced from the wheel when acted upon by the wind or in the careless handling of the line. 90

The invention is simple and economical in 95 construction and serves the purpose for which intended with extremely satisfactory results.

What I claim as my invention, is—

1. In a pulley of the class described, a 100 pulley-wheel, a strap providing a pivotal bearing for said pulley wheel, and extending about the wheel at one side of the axis, and extending beyond the axis in the other direction, and a guide-bar fixedly secured to this end of the strap, and provided with eye openings at its opposite ends. 105

2. In a pulley of the class described, a pulley-wheel, a strap providing a pivotal bearing for said pulley wheel, and extending about the wheel at one side of the axis, 110

and extending beyond the axis in the other direction, and a guide-bar fixedly secured to this end of the strap, and provided with eye openings at its opposite ends, the grooved peripheral edges of said pulley being in tangential relation with both of said eye-openings.

3. In a pulley of the class described, a strap having a loop at one end, a pulley wheel pivoted in said strap, a guide-bar fixedly secured to an extension of said strap beyond the periphery of said pulley wheel, and provided with eye openings in tangential relation with opposite sides of the pulley wheel.

4. In a pulley of the class described, a strap having a loop at one end, a pulley-wheel pivoted in said strap, a guide-bar fixedly secured at right angles to an extension of said strap beyond the periphery of said pulley wheel, and provided with eye openings at each end spaced apart a distance equal to the diameter of the pulley wheel. 20

Signed at Vancouver, B. C., Canada, this 25
22 day of February, 1913.

IVER JOHNSON.
